UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

APPARATUS FOR SHEATHING THE WALLS OF AN EXCAVATION.

1,246,133.

Specification of Letters Patent.

Patented Nov. 13, 1917.

Application filed May 9, 1914. Serial No. 837,373.

To all whom it may concern:

Be it known that I, JAMES C. MEEM, a citizen of the United States, residing at Brooklyn, in the county of Kings and State of New York, have invented certain new and useful Improvements in Apparatus for Sheathing the Walls of an Excavation, of which the following is a full, clear, and exact specification.

10. This invention relates to apparatus for construction and has particular reference to means and apparatus for sheathing an excavation to prevent caving in while a foundation, pier, footing, or other structure, is being erected therein. The invention is especially applicable to the underpinning of buildings or elevated railways during the building of subways. The foundations of existing structures frequently have to be 20 carried down to or below the level of the subway, without disturbance, or allowing the surrounding earth to cave in while the new foundation is being erected.

The invention relates to the mode of excavation wherein the sides of the excavation are sheathed in sections as it progresses downwardly, one section underlying another, and there being as many sections as necessary to reach the required depth. The 30 objects of the invention are to prevent caving in while the work is in progress, and to avoid unnecessary excavation. The method by which these objects are attained consists in placing guides, then placing the sheathing sides in positions determined by these 35 guides to constitute a sheathing section, and then excavating the material within the sheathing section thus constituted. The process is repeated until the excavation reaches the required depth, and then the 40 permanent structure is erected. Preferably, the sheathing sides are set or driven in an inclined position while being guided, and can thus be placed in immediate contact 45 with the earth outside the pit, thereby saving unnecessary excavation. Also, the sides of any section can be set independently of the others and thereby, if desired, the sheathing can be withdrawn as the structural work proceeds, permitting it to be used 50 again. When the excavation has reached the desired depth, the foundation, pier, column, footing or other structure to be erected is commenced, and, where the sheathing is 55 to be recovered, may be considered to be laid

in courses, each course being of a height corresponding to the depth of the adjoining sheathing section. As each course is completed the sheathing sides can be withdrawn into the unfilled portion of the excavation 60 and thus caving in of the surrounding earth is prevented by the structure itself. When the sheathing sections are placed, they are suitably connected to properly locate the guides for the succeeding sections. This also 65 enables the guides to be withdrawn vertically after the sheathing sides have been withdrawn, where it is desired to recover the apparatus.

The apparatus forming a part of the invention comprises the separable or knock-down sheathing sides and guides constructed to be readily set up and taken apart in carrying out the foregoing method.

The invention is illustrated in the accompanying drawings, wherein—

Figure 1 is a plan view of an excavation sheathed according to this invention;

Fig. 2 is a vertical section;

Fig. 3 is a vertical detailed section on an 80 enlarged scale;

Fig. 4 is an elevation of a form of guide;

Fig. 5 is a plan view;

Figs. 6 and 7 are views corresponding to Figs. 1 and 2, but showing a modification in 85 the construction of guide;

Fig. 8 is a side elevation on an enlarged scale;

Fig. 9 is an elevation of a detached guide, and

Fig. 10 is a top plan view of a guide.

1 represents an excavation which at the top where there is not much pressure may have ordinary sheathing 2. 3 represents the lower portion of the excavation, which will 95 be subject to external inward pressure and which employs the special method and apparatus of this invention.

Referring first to Figs. 1 to 5, the guides consists of angle-irons 4 having secured to 100 their face cleats 6, 7, which are spaced apart to form inclined guideways 8 in which the sheathing sides 5 can be slidably guided. The sheathing sides 5 consist of metal plates which are stiffened at their upper edges by 105 angle-irons 9. By properly spacing the guides 4 and sliding the sides 5 into the guideways 8, it will be seen that a sheathing section will be formed which will be rigid against deformation due to outside pressure 110

and which will hold back the external material. Small holes will first be made to receive the guides 4, and then the sides 5 will be driven into position and guided by the guides. If desired, the setting of the sides may be facilitated by making trenches between the guides. After a sheathing section is thus completed, the contained material can then be removed. Thereupon, the process is repeated for the next section below, it being observed that by reason of the inclining of the sides 5 the lower ones can be added without interfering with those previously placed above. As the guides for each section are added, they are connected by links 10, which pass through holes 11, so that the successive guides are all linked together in the form of a chain, but the sides 5 are all independent. These links have the function of 20 positioning the guides, and also constitute connections for withdrawal.

When the excavation has proceeded to the proper depth, the foundation, column, or other structure 12 is then laid, and before it 25 sets the sides 5 of successive sections can be withdrawn, leaving the guides connected together but substantially free of all entanglement either with the structure or with the earth. The guides can then be withdrawn 30 successively, care of course being taken that the connections are made of proper strength. It is not essential to this invention that the sheathing be withdrawn as the structure is erected as in some instances the sheathing 35 will be abandoned.

In some instances, it may be desired to employ wood guides instead of metal, and a suitable construction is illustrated in Figs. 6 to 10. The guides consist of wood pieces 15, 40 which have cleats 16, 17, to form guideways 18. One end of each guide 15 is provided with a dove-tailed groove 19 intersecting the guideway 18 and the other end is provided with a dove-tailed projection 20 which 45 will interlock with the groove 19 of the next guide, thus linking all of the guides together similarly to a chain, as in case of the preceding form, and properly locating the successive guides. The sheathing sides consist of 50 boards 22 which slide in the guideways 18. The edges may be beveled so that they will drive easily. It will be observed that the guideways 18, cleats 16, 17, and dove-tailed 55 grooves 19 are so related to each other that the guides can be interlocked without interference. The method of using this form and building up the structure is substantially the same as that before described.

It will be understood that the shape of the 60 excavation can be varied by varying the angles between the guideways, and the invention is not restricted to the rectangular form herein shown.

In practice, it is found that when the 65 guides are properly spaced, the driving of

the sides acts to firmly set the guides in the earth, and that earth or sand does not flow into the pit through the spaces between the sides of adjoining sections. These spaces enable grout or filling to be put outside the 76 sheathing if it be found desirable. Also, by packing these spaces, the sheathing is readily waterproofed.

By the use of the apparatus of this invention, excavations can be very quickly and 75 cheaply sheathed and foundations or other structures erected therein without danger of caving in, and without unnecessary excavation, while the material is all capable of being recovered after the structure is completed.

Various modifications and changes in the specific structure herein described may be made without departing from the scope of the invention.

Having thus described my invention, I declare that what I claim as new and desire to secure by Letters Patent, is:—

1. A sheathing for an excavation comprising a plurality of superposed sections each 90 comprising corner guides and inclined sides slidably engaging therewith, and means connecting adjacent corner guides.

2. A sheathing for an excavation comprising a plurality of superposed sections 95 each comprising parallel corner guides and downwardly and outwardly inclined sections slidably engaging therewith, said corner guides being in substantial vertical alignment, and the corresponding sides of said 100 sections being substantially parallel.

3. Sectional sheathing for an excavation, each section comprising corner sections, one individual corner section for each corner of the excavation, means to connect such corner sections to the corresponding corner sections above, downwardly and outwardly inclined guides 105 on two sides of each said corner section, and side pieces to engage said guides.

4. Sectional sheathing for an excavation, each section comprising corner guide sections, links to couple such corner guide sections to the corresponding sections above, downwardly and outwardly inclined guide 115 flanges on two sides of each of said corner guide sections, and flat side pieces adapted to have their ends constrained by said flanges.

5. Sectional sheathing for an excavation, 120 each section comprising corner guide sections, means to couple such corner guide sections to the corresponding sections above, downwardly and outwardly inclined guide flanges on two sides of each of said corner 125 guide sections, and flat side pieces adapted to have their ends constrained by said flanges.

6. Sectional sheathing for a square excavation, each section comprising four corner 130

guide members, one such member at each corner, downwardly and outwardly inclined guide flanges on the two sides of each corner guide member that face toward the two nearest remaining corner guide members of the same section, and four flat side pieces adapted to have their ends constrained by said guide flanges.

7. Sectional sheathing for a square excavation, each section comprising four corner guide members, one such member at each corner, means to couple each such corner guide member to the corresponding member of the section above it, downwardly and outwardly inclined guide flanges on the two sides of each corner guide member that face toward the two nearest remaining corner guide members of the same section, and four flat side pieces adapted to have their ends constrained by said guide flanges.

8. Sectional sheathing for a prismatic excavation, comprising sectional corner members lying consecutively along the respective corners of the excavation, each corner member having guide flanges on the two sides thereof that face toward the two other corners of the excavation lying nearest thereto, and side sections extending across all the sides of the excavation, each such section having its ends constrained by said guide flanges, and the latter being disposed so that the side sections lie in planes making a slight angle with the axis of the excavation.

9. Sectional sheathing for a prismatic excavation, comprising sectional corner mem-

bers lying consecutively along the respective corners of the excavation, each corner member having guide flanges on the two sides thereof that face toward the two other corners of the excavation lying nearest thereto, connecting means between consecutive corner members lying along the same corner of the excavation, and side sections extending across all the sides of the excavation, each such section having its ends constrained by said guide flanges, and the latter being disposed so that the side sections lie in planes making a slight angle with the axis of the excavation.

10. Sectional sheathing for a prismatic excavation comprising narrow sectional corner pieces lying consecutively along the respective corners of the excavation, each with guide means on the two sides thereof that face toward the two other corners of the excavation lying nearest thereto, and rectangular side sections extending across all the sides of excavation, each such section having its ends engaging with said guide means on the corner members and constrained thereby so that all the side sections lie in planes making a slight angle with the axis of the excavation.

In testimony whereof I affix my signature, in presence of two witnesses.

JAMES C. MEEM.
